UNITED STATES PATENT OFFICE.

OGDEN MINTON, OF BROOKLYN, NEW YORK, ASSIGNOR, BY MESNE ASSIGNMENTS, TO
UNDERWOOD COMPUTING MACHINE COMPANY, OF NEW YORK, N. Y., A CORPORA-
TION OF NEW YORK.

COMBINED TYPE-WRITING AND COMPUTING MACHINE.

1,280,065.

Specification of Letters Patent. Patented Sept. 24, 1918.

Application filed October 28, 1913. Serial No. 797,714.

To all whom it may concern:

Be it known that I, OGDEN MINTON, a citizen of the United States, residing in Brooklyn borough, city of New York, in the county of Kings and State of New York, have invented certain new and useful Improvements in Combined Type-Writing and Computing Machines, of which the following is a specification.

10 This invention relates to combined type-writing and computing machines and is an improvement on an application of Hans Hanson, filed May 11, 1911, No. 626,550, and an application of John N. Thornton, filed 15 May 22, 1913, No. 769,132.

The machine in connection with which this improvement is shown, is of the Underwood-Hanson type in which the number to be computed is first set up in a nest of index pins digit by digit and subsequently transferred to computing wheels, so that all of the digits of the number accumulated are run up at once.

The machine illustrated is capable of subtraction as well as addition, but by the complementary method, where instead of setting the direct values of the pins, the complements of these values are set and the computing wheels are rotated each a complete 30 revolution less the value of the digit written in the corresponding denominational column.

Various safeguards are provided, whereby the machine may not be set to subtraction at inopportune times. One of these 35 safeguards consists in locking means for preventing the bringing into play of the subtraction-setting mechanism when the general operator, which enables the transfer of an indexed or set-up computation to the 40 computing wheels, is in motion or in any position other than its home position. Another safeguard consists in preventing the actuation of the subtraction-setting mechanism when a previous computation has been 45 set up without having been transferred to the computing wheels, so as to prevent the piling of one set computation upon another. A further safeguard consists in preventing the actuation of the numeral keys in case a 50 setting of the mechanism for subtraction has been partially effected but not completely.

Provision is made whereby the running up of a computation after having been made may be accomplished automatically at the 55 end of a computing zone, by connecting up the general operator in driven relation with a motor.

Provision is also made whereby the computing mechanism may be set for subtraction automatically just before a subtraction computing zone or column is reached, so as to relieve the operative of the necessity of adjusting the mechanism for addition and subtraction at the different computing zones 65 or columns.

When it is desired to operate the type-writing mechanism without computing, the computing mechanism may be operatively disconnected from the typewriting mechanism by the actuation of a non-add key. This non-add key may also be connected so as to render ineffective the automatic control which enables the driving of the general operator at the end of a computing 75 zone or column and also the automatic subtraction-setting mechanism which adjusts the computing mechanism, to set complements of the numbers, just before a subtraction zone or column.

Further provision is made whereby the automatic motor-connecting mechanism and the automatic subtraction-setting mechanism may be thrown out of action independently and locked out of action without resort to the non-add key and without disconnecting the computing mechanism entirely 85 from the typewriting mechanism.

Other features and advantages will hereinafter appear.

Figure 1 is a diagrammatic section taken from front to rear with parts omitted for the sake of simplicity, and showing the subtraction-setting mechanism in its ineffective state.

Fig. 2 is an enlarged detail section similar to Fig. 1, in which the subtraction-setting mechanism is shown in action and just about to complete its operation with the "9" pin setting bail just released ready to return to its cleared position. This figure also shows the automatic throw-out mechanism in its ineffective position.

ing means for the automatic motor connection and the automatic subtraction-setting connection in its permanent effective position so that these parts are incapable of action until released manually.

Fig. 4 is a detail skeleton perspective view showing the connection of the motor-tripping and subtraction-setting-tripping mechanism, and showing the subtraction-setting mechanism in its dormant or ineffective position.

Fig. 5 is a detail view in horizontal section of the manual key whereby the mechanism may be set for subtraction and showing the same in its unactuated position.

Fig. 6 is a view exactly similar to Fig. 5, with the exception that the subtraction key has been pressed in and locked in its actuated position.

Fig. 7 is a detail view showing the subtraction bar in full lines in its actuated position and in dotted lines in its unactuated position, with the lock which prevents the bringing into play of the subtraction-setting mechanism when the general operator is in motion or in a position other than its home position, in its effective position in full lines and in its ineffective position in dotted lines.

Fig. 8 is a skeleton perspective view showing the details whereby the computing mechanism is disconnected from the typewriting mechanism and rendered ineffective, together with the means for throwing the automatic motor-connecting mechanism and the automatic subtraction-setting mechanism out of action. In this view the non-add key is shown to have been actuated and locked in its actuated position, so that the computing mechanism is disconnected from the typewriting mechanism, but the automatic motor trip and automatic subtraction-setting mechanism are only temporarily thrown out of action.

Fig. 9 is an enlarged detail view showing the means for unlocking the non-add key and in the act of unlocking the non-add key when the general operator comes into play subsequently to the actuation of the non-add key.

Fig. 10 is a detail plan view showing the means for preventing the actuation of the subtraction-setting bar while the motor and its trip are in action, which means also prevents the drive of the general operator by the motor when the subtraction-setting bar is in the act of moving to its subtraction-setting position or when it has been but partially actuated.

Alphabet keys 1 and numeral keys 2 depress levers 3 to rock bell cranks 4, which are connected to swing type bars 5 up rearwardly against the front side of a platen 6 mounted on a carriage 7. The carriage 7 travels step by step under the control of an escapement mechanism indicated in general

at 8. This escapement mechanism includes a rack 9 mounted on the carriage 7 to engage a pinion 10 connected to an escapement wheel 11, which is controlled in its rotation by a pair of pawls 12, which in turn are rocked back and forth by a universal frame 13. This frame 13 is actuated at the swinging of any of the type bars, by a heel 14 carried by each of the type bars.

Besides a step-by-step movement of the carriage 7, provision is made for a jump movement of the carriage as in tabulating. For this purpose, tabulating keys 15 depress key levers 16 so as to thrust up decimal plungers 17 into the path of stops 18 adjustably mounted on a rack 19 carried by the carriage 7. Before the carriage 7 can move, however, under the traction of a spring barrel, not shown, it must be released from the escapement mechanism 8. Each of the plungers 17 is provided with a shoulder 20 which engages a universal arm 21 on a lever 22, so that as a plunger is thrust upwardly to move into the path of one of the stops 18, it will rock the lever 22 and thus draw down on a link 23 to rock a lever 24 carrying at its forward end a bearing roller 25, which underlies the rack 9, thereby raising the same out of engagement with the pinion 10 and permitting a movement of the carriage under the traction of the spring barrel, not shown, until the next stop 18 abuts against the projecting plunger 17.

In addition to operating the two actions to print the numbers, the numeral keys 2 also index or set up preliminary representation of the digits in the computing mechanism indicated in general at 26. To do this, each of the numeral keys from "1" to "9" is provided with a depending bar 27, which engages an arm 28 on a rock shaft 29 arranged to operate a linkage 30. There is one of these linkages for each of the numeral keys from "1" to "9", and they are each engaged by an arm 31 carried by the accordant one of the rock shafts 29. The lower reaches 32 of the linkages 30 are employed for the purpose of setting index pins 33 provided on denominational column-selecting members 34. The pins 33, however, are normally located out of alignment with the lower reaches 32, so that if any reach were depressed, it would pass idly between two transverse rows of the pins 33.

In order, then, to enable the setting of the pins 33, a denominational selecting mechanism is provided which will accord the denominational member 34 on which a pin is set with the digit column in which the digit is being printed at any particular instant. For this purpose, there is provided on the carriage 7, one or more tappets 35, which, during the travel of the carriage, come *seriatim* into engagement with a series of jacks 36, so as to rock the same. These jacks en-

gage, at their rear ends, with thrust rods 37, so as to depress these thrust rods and thus rock levers 38, which in turn actuate linkages 39. The linkages 39 in turn rock bell 5 cranks 40, which engage individually with lugs on accordant ones of the denominational members 34, so as to shift them forwardly to such a position that their pins 33 lie beneath the lower reaches 32 of the pins.

10 setting linkages 30.

Inasmuch as the carriage 7 travels from right to left while indexing proceeds from left to right, the order of bringing into play of the denominational members 34 is inverted to the order of actuation of the jacks 36. This is accomplished by the transposition mechanism including the levers 38, the linkages 39 and the bell cranks 40. The specific action of this mechanism is described and shown in an application of Frederick A. Hart, filed August 6, 1913, No. 783,258, and forms no part of this invention. However, the result of this action is that the index pin-bearing members 34 20 are shifted successively and in order starting with the one at the extreme left and proceeding to the right, so as to correspond with the bringing of the letter spaces on the carriage 7 corresponding to the writing of the several digits, to the printing point of the typewriter, so that the denominations of the digits as indexed in the computing mechanism are accordant with the denominations of these digits as they are 30 printed by the typewriting mechanism.

After all of the digits of a number to be computed have been indexed on the several pin-bearing denominational members 34, it is necessary to run up these numbers in 40 the computing heads, which include a series of computing wheels 41, so that the numbers as run up on the computing wheels can be exhibited through a sight opening 42 provided in the casing 43 of the machine. 45 To accomplish this, each of the computing wheels 41 is provided with a gear 44 engaged by a rack 45 carried by the accordant one of the denominational members 34.

The general operator 46 is provided with 50 a cross bar 47, which, at a forward motion of the general operator, engages with such of the index pins 33 as have been set, giving their denominational members 34 forward movements according with the particular pins set and corresponding to the numeral keys actuated in the columns to which their members 34 correspond.

The general operator 46 may be actuated by hand, by means of a crank on a shaft 47^a 60 having one or more segments 48 engaging pinions 49, which in turn mesh with rack bars 50 carried on the side plates of the general operator. The general operator also may be driven by power, derived from 65 a motor at the depression of a key 51, which

rocks a lever 52 to remove a stop pin 53 from engagement with a clutch closer 54. This clutch closer 54 acts in the manner described in an application of Frederick A. Hart, filed Dec. 9, 1910, No. 596,451, to connect the general operator 46 in driven relation with a motor, so that the general operator is given a single back-and-forth movement.

On the return movement of the general operator, tens-carrying is effected for the computing wheels 41, and the denominational members 34 are returned by the cross bar 47 engaging lugs 55 provided on all of these members.

80 If it is desired to drive the general operator 46 back and forth at a predetermined point in the travel of the carriage 7, this may be done automatically by providing one of the stops 18 with an extension sufficient to come into engagement with a motor trip 56, so as to rock the same in the manner disclosed in said Thornton application, No. 769,132. This trip 56 will be rocked to draw on a link 57, which in turn will rock a bell 90 crank 58 to remove a latch 59 from above a lever 60, so that the latter may rock under the pull of a spring 61, whereby the opposite end of the lever 60, which engages a pin 62 on the key 51, will depress the latter to 95 remove the stop pin 53 from in front of the lug on the clutch closer 54, thereby enabling the connection of the general operator in driven relation with the motor, not shown.

100 In addition to the present machine being capable of performing straight addition, it is also capable of performing subtraction. For this purpose, the pin-setting mechanism including the shafts 29, the linkages 30 and the arms 31, is of an adjustable type, as explained in said Hanson application, No. 626,550, so that it may be changed to set pins corresponding to the complements of the digits represented by the numeral keys struck instead of the direct values. That is 105 to say, the mechanism is arranged to carry on what is called "complementary subtraction," which consists in rotating all of the computing wheels a complete revolution less amounts corresponding to the values of the 110 keys actuated for the particular computing wheels. To do this, the shafts 29 are shifted in the manner described in said Hanson application above referred to, to bring the arms 31 out of engagement with pins on one 115 side of the upper reaches of the linkages 30, and into engagement with opposite pins on the juxtaposed upper reaches of these linkages.

120 The shafts 29 are shiftable in unison by 125 a universal bar 63, which engages a series of alined notches provided in the shafts 29. The universal bar 63 is pivoted at its upper edge and is provided with an arm 64 which is engaged with and actuated by an arm 65 130

on a rock shaft 66. The rock shaft 66 is provided with a second arm 67, which is bifurcated to engage a pin 68 provided on a subtraction bar 69. The subtraction rod 5 69 is normally locked in a forward position against the tension of a spring 70 by a detent 71, which engages a notch 72 provided in the subtraction bar 69.

In order to release the detent 71, and thus 10 permit the spring 70 to retract and draw the subtraction rod 69 with it, the detent 71 is secured to a shaft 73, which is also provided with an arm 74, whereby this shaft may be rocked against the tension of a 15 spring 75^a. The rocking of this shaft 73 may be done manually by means of a subtraction key 75, which projects outwardly from the front part of the casing 43, and has a subtraction rod 76 extending rear- 20 wardly to pivotal engagement with the arm 74. It will readily be seen that when the subtraction key 75 is pressed rearwardly, the shaft 73 will be rocked, removing the detent 71 from engagement with the notch 72, 25 so as to permit the spring 70 to retract the subtraction bar 69, thus rocking the bell crank comprising the arms 67 and 65, whereby the universal bar 63 will be rocked forwardly to shift the shafts 29 and the arms 31 carried thereby from their adding to 30 their subtracting position.

In addition to re-arranging the pin-setting mechanism to set complementary numbers, it is also necessary to set the "9" pins, 35 as explained in the said Hanson application, No. 626,550. For this purpose, each of the "9" pins is provided with a reduced neck engaged by a shifter lever 77, which is pivoted in each case on the accordant denominational bar or member 34. These shifter levers 77 underlie a universal bail 78. The bail 78 is held in its uppermost position clear of the levers 77, by a spring 79 coiled about a rock shaft 80 on which the bail 45 is secured.

When the subtraction bar 69, however, 50 snaps rearwardly under the traction of the spring 70, a hook 81 pivotally mounted on the bar 69 and engaging in a notch 82 provided in an arm 83 also secured to the rock shaft 80, will rock the shaft 80 and the bail 78, so that the latter will come down and depress the forward ends of the levers 77 and thus set the "9" pins. Before the subtraction 55 bar 69 has entirely completed its rearward motion, an arm on the hook 81 will come into engagement with a stop or disconnector 84, whereby this hook will be rocked against the tension of a spring 85 out of engagement 60 with the notch 82 permitting the spring 79 to act to retrieve the bail 78 and thus leaving the "9" pins and their levers 77 free and clear in their set position. If by any chance the spring 79 should not act, the cross bar 65 47 of the general operator will, on a sub-

sequent motion, engage an extension 86 on the arm 83, returning the bail and connected parts to their normal raised position.

In addition to setting for subtraction manually, means is provided whereby the 70 mechanism may be adjusted for a subtraction computation automatically at a pre-determined point in the travel of the carriage. For this purpose, there is provided on the rack 19 carried by the carriage 7, a 75 subtraction tappet 87, which has a portion 88 arranged to actuate the motor trip 56 at the end of a subtraction zone and which is also provided with an extension 89 extending for substantially a computing zone, 80 which extension projects to such an extent that it will engage a trip 90 and rock the same when a subtraction zone is reached. The trip 90 is connected to pull on a link 91, so as to rock a bail bell crank 92, which 85 is connected to withdraw a latch 93 from beneath one arm of a bell crank 94 loosely mounted on the shaft 73.

The bell crank 94 is provided with a second arm 95, to which are secured a pair 90 of springs 96 and 97, which tend to rock the bell crank 94, which is normally prevented by the latch 93. When this latch, 93 however, is withdrawn in the manner described, the bell crank 94 will be rocked, so 95 that a short arm 98 carried thereby will engage a lug 99 on an arm 100 secured to the shaft 73. The shaft 73 will thus be rocked to withdraw the detent 71 from engagement with the notch 72, permitting the subtraction 100 bar 69 to be snapped rearwardly to its subtraction-setting position by the spring 70.

The purpose of the arms 98 and 100 is to 105 permit a lost motion between the shaft 73 and the bell crank 94, so that the subtraction-setting mechanism may be brought into play manually by the actuation of the subtraction key 75, without disturbing the bell crank 94 and the mechanism controlling the same.

The numeral keys 2 are locked against 110 actuation during a subtraction-setting operation, so that in case the mechanism should happen to be in half-set position, the numeral keys will be prevented from operation. 115 To do this, use is made of the normal key-locking mechanism shown and described in an application of Frederick A. Hart, filed December 10, 1908, No. 466,836, which includes a rod 101 extending from each of the 120 thrust rods 27 on the numeral keys 2, and which is adapted to engage between pairs of pivotally-mounted crowding members 102, which act to prevent the entrance of any other of the rods 101 and thus prevent 125 the depression of any other of the numeral keys after one has been actuated.

To make use of this mechanism, the arm 83 on the bail 78 is provided with a cam heel 103 which engages an arm 104 forming 130

part of a bell crank 105 loosely mounted on the shaft 73. It thus occurs that when the bail 78 is rocked to set the "9" pins, the bell crank 105 will be rocked to pull on a link 106, which in turn will swing an arm 107 secured to a shaft 108. The shaft 108 has loosely mounted thereon an intruding arm 109, which is connected by a spring 110 to an arm 111 secured to the shaft 108, so 5 that the intruding arm 109 while not moving rigidly with the shaft 108, will normally be moved up between two of the crowding members 102 and thus prevent the actuation of any of the numeral keys 2. The 10 reason of the yielding connection formed by the spring 110, is to avoid the breaking of any of the parts in case one of the numeral keys should be depressed and the intruding arm 109 happen to be between two of the 15 crowding members 102, there being room for but one intruding member between these crowding members.

When the hook 81 releases the bail 78 and it returns to its normal position, the key-locking mechanism just described will be released by the returning of the parts to their normal position, by means of a spring 112, so that the numeral keys may be actuated to set up a computation for the subtraction operation. However, if the bail 78 and the parts connected thereto should happen to be disconnected from the hook 81, or should become stuck in their actuated position, then the numeral keys would be locked against 30 actuation until the derangement of the parts had been adjusted.

After a subtraction setting and during the running up of a subtraction computation into the computing wheels 41, the spring 70 40 is automatically retensioned and the subtraction bar set to a normal passive position corresponding to an adding action by the cross bar 47 engaging a lug 113 provided on the subtraction bar 69. The spring 70 and the 45 bar 69 will be held in a passive position by the latch 71 engaging in the notch 72 automatically.

It is undesirable to have the general operator driven while the subtraction-setting 50 bar 69 is in the act of moving to its subtraction-setting position; hence, it is necessary to prevent the motor from being automatically connected up to the general operator at such time by the motor trip 56, as might 55 happen where the operation of the machine is very rapid. It is further undesirable to bring into play the subtraction-setting bar at the moment when the general operator is being connected in driven relation with the 60 motor by an actuation of the automatic motor trip.

To prevent these actions from taking place automatically, there is provided a safeguard lock, which consists of a roll-back 190, pivoted at 191 in a fixed portion of the frame 65

and arranged to swing from a position clear of a ward 192 on the subtraction bar 69 to a position obstructing the movement of said ward and subtraction bar 69 when the motor trip 56 is actuated. To do this, there is secured on the latch 59 an arm 193 (Figs. 4 and 10) bent over to extend into a notch 194 provided in the roll-back 190. 70

It will thus be seen that when the motor trip 56 is rocked to connect up the general 75 operator in driven relation with the motor, the latch 59 will be withdrawn so as to rock the roll-back 190 to a position in the path of the ward 192, thereby preventing the subtraction bar 69 from being brought into play 80 by its spring 70. As soon, however, as the latch 59 returns to its normal position, the roll-back 190 will be withdrawn from its locking position, permitting the bringing into play of the subtraction bar 69 and the subtraction-setting mechanism. On the other hand, if the subtraction bar should be partially actuated, the ward 192 would be in the path of the roll-back 190, preventing it and the automatic tripping mechanism connected thereto from being actuated, so that the general operator cannot be automatically driven at this time. The ward 192 is cam-shaped at one end to move aside the roll-back 190 in case it should happen to be in its 95 effective position when the subtraction bar 69 is being returned to its silent position.

If it is desired to throw the computing mechanism out of operation, a non-add key 114 may be pressed inwardly, so as to operatively disconnect the computing mechanism from the typewriting mechanism. 100

Before going into details of this mechanism, it would be well to mention the fact that the tappets 35 are not normally in a 105 position to actuate the jacks 36. That is to say, these tappets 35 are each pivoted on a bar 115 and rest in a depressed position on a bar 116, so that if they were to travel in this position beneath the jacks 36, they 110 would clear them without operating them. However, when a tappet 35 comes into a computing zone, a zone-controlling roller 117 cams the tappet 35 upwardly by engagement with the following roller 118 on the tappet 115 and thus raises the tappet to such a height that it will engage and operate the jacks 36 in succession. The zone-controlling roller 117 is mounted on a pair of arms 119 secured to a rock shaft 120 and is normally held in 120 a position to engage the following roller 118 by means of a spring 121. The zone-controlling roller and the mounting therefor, however, can be moved against the tension of the spring 121 to clear the zone-controlling roller 117 from the path of travel of the following roller 118, so that if a tappet should come along at such a time and the zone-controlling roller was moved to its ineffective position, the tappet would pass idly 125 130

beneath the jacks 36 without being raised to action.

Now, then, if the non-add key is pressed inwardly, it forces its stem 122 before it, 5 which stem is pivotally connected at 123 to a thrust rod 124, so that the latter is actuated to rock a bell crank 125 to which it is pivoted. The bell crank 125 is provided with an arm 126 having a pin 127 underlying an 10 arm 128 on the rock shaft 120. It will thus be seen that when the non-add key 114 is pressed inwardly, it moves the zone-controlling roller 117 against the tension of the spring 121, to its ineffective position, there- 15 by silencing the control of the denominational members 34 from the typewriter carriage 7. Under these circumstances, the numeral keys 2 may actuate the pin-setting mechanism idly as the lower reaches of the 20 linkages 30 will pass idly between the rows of pins 33.

Connection is made whereby the non-add key 114 not only silences the denominational control, but also silences the automatic 25 motor-trip-controlling mechanism and the automatic subtraction-setting mechanism whereby even if the carriage in its travel should actuate trips 56 and 90, the general operator, in the first instance, would not be 30 automatically actuated, and a subtraction-setting mechanism, in the second instance, would not be automatically brought into play. To do this, the thrust link 124 is provided with a pin 129, which engages a lever 35 130 pivoted intermediate its ends on a shaft 131, and carrying at its far end a pin 132 which extends through a slot 133 provided in a latch arm 134 pivotally mounted on the shaft 131.

40 Thus when the non-add key 114 is pressed inwardly, it causes the thrust link 124 to rock the lever 130 against the tension of the spring 96, which is connected thereto. This moves the pin 132 in the slot 133, permitting the spring 97, which is connected to the latch arm 134, to draw the latch arm 134 into the Fig. 8 position, when a hooklatch 135 will come into engagement with a stud 136 provided on the bell crank arm 94, which 45 arm, in its normal operation, releases the latch 71 on an actuation of the subtraction trip 90. The latch 135 is also provided with a toe 137, which engages over a stop 138 provided on the lever 60.

50 It will thus be seen that while the non-add key is in its operated position, the bell crank will be prevented from rocking under the impulse of the springs 96 and 97, and also the lever 60 will be prevented from 55 rocking under the impulse of its spring 61. Under these circumstances, even if the latches 93 and 59 are withdrawn, the subtraction-setting mechanism and the clutch closing mechanism will not be operated, so 60 that the automatic means for controlling

the setting for subtraction and the driving of the general operator by the motor, are silenced.

A lock 139 is pivotally connected to the lever 130, so as to be retracted thereby when 70 said lever is actuated, and said lock projects outwardly through an opening in the back of the casing 43, and is provided with a shoulder 140 to engage a ledge 141 at the bottom of said opening, for the purpose of 75 retaining the lever 130, the latch arm 134 and the parts connected thereto, in their silencing positions. The lock 139, however, is not retracted far enough to engage its shoulder 140 with the ledge 141 when the 80 non-add key 114 is pressed into its active position, as will be understood from Fig. 8, but must subsequently be positively forced back into its locking position (Fig. 3) by 85 hand. It is therefore evident that so long as 85 the non-add key 114 is held in its set position, the automatic motor control and the automatic subtraction-setting control will be thrown out of play, but unless the lock 139 is positively set by hand independently, 90 these automatic mechanisms will be returned to activity just as soon as the non-add key 114 returns to its inactive position. The lock 139, then, enables the permanent 95 silencing of the automatic motor-connecting control and the automatic subtraction-setting control independently of the activity of the non-add key 114. That is to say, the computing mechanism can be actively controlled from the carriage 7 through the 100 tappets 35 and the jacks 36, while the automatic bringing into play of the motor and the subtraction-setting mechanism is cut out of use for the time being.

This differential locking is made possible 105 by the fact that the latch arm 134 has a relative movement or lost motion with respect to the lever 130, so that while the movement of the thrust link 124, under the push of the non-add key 114, is insufficient 110 to bring the lock 139 into a position where the locking action can take place, this lock may subsequently be forced in by hand until the shoulder 140 engages the ledge 141 to effect such action without further disturbing the position of the latch arm 134.

115 It will be noted in passing that the spring 96 is considerably stronger than the spring 97, so that when the non-add key 114 is returned to its inactive position and the lock 139 released, then the spring 96 will return the lever 130 and the latch arm 134 to their inactive positions.

120 The non-add key 114 when once pressed in to disconnect the communicating mechanism from the typewriting mechanism, is locked in its actuated position, so as to enable the operative to use both hands in operating the machine. For this purpose, there is provided on the thrust link 124, 125 130

a pin 142 which engages in an L-slot 143 in a stationary portion of the frame of the machine. The reach of this L-slot extends horizontally to guide the motion of the link 124 while being pressed rearwardly and joins with the bend or offshoot of the L-slot at a point where the pin 142 reaches the end of its movement, so that the weight of the link 124 aided by a spring 144, will cause the pin 142 to drop into the offshoot, preventing the return of the link 124 and the non-add key 114. The parts are shown in this position in Fig. 8. To return the non-add key 114 and the link 124 and the parts connected thereto to their inactive positions, it is necessary to actuate the general operator either manually or from the motor.

The releasing mechanism includes a cam 145 secured on the shaft 47^a, so as to rotate therewith. This cam normally has a depressed portion thereof in register with a releasing rod 146 when the general operator is in its home position. When, however, the general operator is moved forward, the shaft 47^a will be rotated through the pinions 49 and the segments 48, so as to bring the rise of the cam into engagement with the releasing rod 146, so as to raise the same against the tension of the spring 144, which is connected thereto. This rod 146 is also connected to the thrust link 124, so that it will raise the latter to bring the pin 142 out of the offshoot of the L-slot 143, permitting the spring 121, and in case the lock 139 is not in play, the spring 96, to return the non-add key 114 to its inactive position. In Fig. 9, the pin 142 is shown as having been raised, by the action of the parts 145 and 146, from the bottom to the top of the offshoot of slot 143. The releasing rod 146 is guided in its movement by having a pin-and-slot connection with a bracket 147 loosely mounted on the shaft 47^a.

It is undesirable to permit the actuation of the subtraction-setting mechanism either automatically or manually when the general operator is in motion or in any position other than its normal or home position. To prevent such inopportune action of the subtraction-setting mechanism the subtraction bar 69, which is provided with a gooseneck 148 embracing and guided by a grooved hub 149 on the shaft 47^a, is provided with a pin 150 engageable by a locking dog 151 pivotally mounted on the shaft 47^a normally under a tendency, owing to the pull exerted upon said dog by the spring 153, to drop behind the pin 150 and prevent the rearward traction of the subtraction bar 69 by the spring 70, even though the locking detent 71 should be released. The dog 151, however, is prevented from moving to its effective or locking position when the general operator is in its inactive home position, by an arm 154 provided on

the dog 151 engaging a pin 155 on an arm 156 secured on the shaft 47^a.

When, however, the general operator starts in motion, the arm 156 and pin 155 travel away from the arm 154, permitting the spring 153 to force the dog 151 in back of the pin 150 on the subtraction bar 69, thereby preventing the bringing into play of the subtraction-setting mechanism until the general operator has once more returned to its home position and the arm 156 has once more removed the dog 151 from engagement with the pin 150 against the tension of the spring 153.

If it were possible to continue on with a second computation after the first had been indexed by a setting of the index pins 33 without the required operation of the general operator, this would cause a piling up of computations giving an inaccurate result. Hence it becomes necessary to prevent the operative from neglecting to actuate the general operator in case the automatic control thereof should be thrown out of action or not adjusted for action at any particular computing zone.

To warn the operative that a computation has been indexed without transferring it to the computing wheels, use is made of the blinding and locking mechanism set forth in an application of Frederick A. Hart, filed July 17, 1911, No. 638,794. This mechanism includes a special jack similar to the jacks 36 but placed at the left end of the series so as to come into play after all of the others have been actuated. This jack actuates a thrust link, similar to the links 37, when it itself has been rocked by a tappet 35, so that a lug 157 on this thrust link will engage and rock a bell crank 158, which in turn withdraws a latch 159 from engagement with a notch 160 provided in an arm 161 secured on a shaft 162. The shaft 162 is provided with a pair of arms 163 extending upwardly to a point where they are provided with a cross bar 164, which is arranged to be swung over the tops of the numeral keys 2 by means of a spring 165, which rocks the shaft 162. The rocking of the shaft also swings an arm 166 secured thereto, which in turn draws on a link 167 to swing a shield or blind 168 between the sight aperture 42 and the computing wheels 41, thereby covering the numbers on these computing wheels which are normally exposed. There is thus provided a double means of warning the operative that a computation has been indexed and not transferred to the computing wheels, as he cannot operate the numeral keys and cannot see the computing wheels 41.

In addition to the above safeguard, it is necessary to prevent a subtraction setting in case of an indexed computation still extant in the nest of pins 33. To do this, the shield 130

or blind 168 is provided with an extension arm 169 having a pin 170 arranged at a rocking of the shield or blind 168, to engage in a notch 171 forming a hook on the forward end of the subtraction bar 69. This, then, will prevent an actuation of the subtraction bar 69 under the traction of the spring 70 until the indexed computation has been transferred to the computing wheels 41. The forward end of the subtraction bar 69 is beveled to permit it to cam by the pin 170 in case the latter should be in its effective position when the subtraction bar 69 is being moved forward to its 15 effective position.

The return of the lever 60 and the bell crank 94-95 is effected by the general operator during a movement subsequent to their coming into play, so that the latches 20 59 and 93 can once more lock the lever and bell crank in their set position. In the case of the lever 60, this is accomplished by a cam 172 on one of the side plates of the general operator engaging an extension 173 on 25 the lever 60. In the case of the bell crank the shaft 73 is provided with an arm 174 having a cam head 175, which is engaged by the cross bar 47 of the general operator during the movement thereof. The rocking 30 of this arm rocks the said bell crank of which it forms a part, and raises the arm 94, retensioning the springs 96 and 97, and thus permitting the return of the latch 93 to its effective position.

35 To maintain the computing mechanism in a subtracting state after the subtraction key 75 has been actuated, a lock bolt 176 may be pressed in to cause a disk head 177 thereon to engage in back of a disk 178 on a pin 179 provided on the thrust rod 76 of the subtraction key 75, as shown in Fig. 6. In case it is desired to unlock the subtraction key 75, it is merely necessary to press the subtraction key in a little farther, when the disk 178 will be 40 moved out of engagement with the disk head 177, so that the latter can be pressed outwardly into its normal or ineffective position, shown in Fig. 5, by an automatic releaser comprising a spring 180 secured to 45 the rod 76 and urging a pin 181 against the disk head 177. In other words, in order to unlock the subtraction key 75 after it has once been locked in its actuated position, it is merely necessary to re-actuate said key 50 when the bolt 176 will be automatically shoved back to its ineffective position, it being understood that the pressure upon the key is not removed until the return movement of the bolt has taken place.

55 60 It will thus be seen that the computing mechanism may be set either manually or automatically for subtraction, with the necessary safeguard for preventing such setting at inopportune times; as when the general operator is in motion or in position

other than a home position, or when a computation has been set up without being transferred to the computing wheels.

Further, it will be evident that the automatic mechanism for driving the general operator and for setting the mechanism for subtraction without thought on the part of the operative, may be thrown out of action when the computing mechanism itself is thrown out of action, or independently without throwing out of action the computing mechanism.

Variations may be resorted to within the scope of the invention, and portions of the improvements may be used without others.

Having thus described my invention, I claim:

1. The combination, with a computing mechanism, including computation-controlling devices, and a general operator for said mechanism; of a subtraction-setting mechanism acting, when actuated, to set certain of said controlling devices for engagement by said general operator when the latter is in motion; and locking means brought into play automatically consequent upon motion being imparted to the general operator, for preventing the action of said subtraction-setting mechanism while said general operator is in motion.

2. The combination, with a computing mechanism, including computation-controlling devices and a general operator for said mechanism having a movement in action away from a stationary home position and back to the same; of a subtraction-setting mechanism acting, when actuated, to set certain of said controlling devices for engagement by said general operator when the latter is in motion; and locking means acting automatically, when the general operator is in any other than its home position, to prevent the action of said subtraction-setting mechanism.

3. The combination, with a computing mechanism, including computation-controlling devices, and a general operator for said mechanism; of a subtraction-setting mechanism acting, when actuated, to set certain of said controlling devices for engagement by said general operator when the latter is in motion; locking means brought into play automatically consequent upon motion being imparted to the general operator, for preventing the action of said subtraction-setting mechanism while said general operator is in motion; and means actuated by said general operator, on returning to normal position, for automatically rendering said locking means ineffective.

4. The combination with a computing mechanism, of a subtraction-setting mechanism for said computing mechanism including a subtraction bar, a spring for actuating said bar, a general operator for said comput-

ing mechanism including a rotatable shaft, a lock engaging said subtraction bar to prevent the actuation thereof by said spring, and means on said shaft for releasing said lock solely when said general operator is in its unactuated position.

5. The combination with a computing mechanism, of a subtraction-setting mechanism for said computing mechanism including a subtraction bar, a general operator for said computing mechanism including a shaft rotatable at the motion of said general operator, a pin on said bar, a dog on said shaft, a spring normally urging said dog into engagement with said pin to lock said bar against movement, and means on said shaft for preventing the action of said spring while said shaft is stationary.

6. The combination, with computing mechanism, and a general operator therefor; of subtraction-setting mechanism; means tending to automatically actuate said setting mechanism; a traveling carriage; a lock for said setting mechanism releasable by said carriage, just as the latter enters a subtraction zone, to permit the actuation of said setting mechanism by said automatic means; a drive for said general operator automatically set in action just as the carriage leaves a subtraction zone; said general operator acting, during its initial movement, to restore said setting mechanism to normal position; and an automatically-acting guard lock for said setting mechanism, arranged to come into action during said initial movement of the general operator and prior to the first-named lock, so as to hold the setting mechanism against movement out of normal position under the action of said automatic means, during the return movement of the general operator, until said first-named lock again becomes effective.

7. The combination, with computing mechanism, and a general operator therefor; of subtraction-setting mechanism, including a movable controlling bar; means tending to automatically actuate said bar; a traveling carriage; a lock for said bar releasable by said carriage, just as the latter enters a subtraction zone, to permit the actuation of said bar by said automatic means; a drive for said general operator, automatically set in action just as the carriage leaves the subtraction zone; said general operator acting, during its initial movement, to restore said bar to normal position; and an automatically-acting guard lock for said bar, arranged to come into action during said initial movement of the general operator and prior to the first-named lock, so as to prevent said bar from moving out of normal position, under the action of said automatic means, during the return movement of the general operator, until said first-named lock again becomes effective.

8. The combination with computing mechanism; and a general operator therefor; of subtraction-setting mechanism; means tending to automatically actuate said setting mechanism; a lock for said setting mechanism, releasable to permit the actuation thereof by said automatic means; said general operator acting, during its initial movement, to restore said setting mechanism to normal position; and an automatically-acting guard lock for said setting mechanism, arranged to come into action during said initial movement of the general operator and prior to the first-named lock, so as to hold the setting mechanism against movement out of normal position under the action of said automatic means, during the return movement of said general operator, until said first-named lock again becomes effective.

9. The combination, with computing mechanism, and a general operator therefor; of subtraction-setting mechanism, including a subtraction bar; means tending to automatically actuate said bar; a detent normally holding said bar against actuation by said automatic means, but releasable therefrom to permit such actuation; said general operating acting, during its initial movement, to restore said bar to normal position; and an automatically-acting guard lock for said bar, arranged to come into action during said initial movement of the general operator and prior to said detent, so as to hold the bar against movement out of normal position, under the action of said automatic means, during the return movement of said general operator, until said detent again becomes effective.

10. The combination with a computing mechanism, of a subtraction-setting mechanism for said computing mechanism, a spring normally under a tension tending to bring said subtraction-setting mechanism into play, detent means for preventing the action of said spring and thus preventing the bringing into play of said subtraction-setting mechanism, and manual controlling means for releasing said detent means.

11. The combination with a computing mechanism, of a subtraction-setting mechanism for readjusting said computing mechanism so as to carry on a subtraction computation, a spring tending to bring said subtraction-setting mechanism into play, a detent for preventing the action of said spring and thus preventing the bringing into play of said subtraction-setting mechanism, a spring holding said detent to its work, and a manually-operable key for releasing said detent against the tension of said last-mentioned spring.

12. The combination with a computing mechanism, of a subtraction-setting mechanism for readjusting said computing mecha-

nism so as to carry on a subtraction computation, a spring tending to bring said subtraction-setting mechanism into play, a detent for preventing the action of said spring and thus preventing the bringing into play of said subtraction-setting mechanism, a spring holding said detent to its work, a manually-operable key movable in one direction to release said detent against the tension of said last-mentioned spring, locking means for holding said key against return movement after having been moved in such direction, and automatically acting releasing means brought into play when said key is moved farther in such direction for releasing said locking means to permit the automatic return of said key.

13. The combination, with a set of computing wheels, and driving means therefor; ofvaluating mechanism settable to determine the extent of drive, said valuating mechanism being restored to normal position at the conclusion of the driving operation; subtraction-setting mechanism, including a movable controlling element; and a lock arranged to automatically engage said controlling element at the conclusion of the setting of said valuating mechanism, so as to prevent actuation of said setting mechanism until the restoration of the valuating mechanism.

14. The combination, with a set of computing wheels, and driving means therefor; ofvaluating mechanism settable to determine the extent of drive, said valuating mechanism being restored to normal position at the conclusion of the driving operation; subtraction - setting mechanism, including a movable controlling element; a lock engageable with said controlling element to prevent actuation of said setting mechanism; and means for bringing said lock into action automatically consequent upon the operation of said valuating mechanism, and automatically releasing the same consequent upon its restoration.

15. The combination, with a set of computing wheels, and driving means therefor; ofvaluating mechanism settable to determine the extent of drive, said valuating mechanism being restored to normal position at the conclusion of the driving operation; subtraction-settting mechanism, including a subtraction bar provided with a shoulder; a lock engageable with said shoulder to prevent actuation of said bar; and means for bringing said lock into action automatically consequent upon the operation of said valuating mechanism, and automatically releasing the same consequent upon its restoration.

16. The combination with a set of computing wheels, and driving means therefor; of valuating mechanism settable to determine the extent of drive, said valuating mechanism

being restored to normal position at the conclusion of the driving operation; subtraction-setting mechanism, including a movable controlling element; a blinding device for said wheels having a locking arm thereon engageable with said controlling element to hold the same against operation; and means for bringing said blinding device and said locking arm into action automatically consequent upon the setting of said valuating mechanism, and automatically throwing the same out of action at the restoration of said valuating mechanism.

17. The combination, with a set of computing wheels, and driving means therefor; of valuating mechanism settable to determine the extent of drive, said valuating mechanism being restored to normal position at the conclusion of the driving operation; subtraction-setting mechanism, including a movable controlling bar having a notch therein; a movable blinding device for said wheels; means for bringing said blinding device into action automatically consequent upon the setting of said valuating mechanism, and throwing the same out of action automatically at the restoration of said valuating mechanism; and a locking arm connected to said blinding device to move therewith, said arm arranged to successively engage and disengage the notch in said bar.

18. The combination, with computing mechanism, including a set of computing wheels, and driving means for said wheels; ofvaluating mechanism settable to determine the extent of drive, said valuating mechanism being restored to normal position at the conclusion of the driving operation; subtraction-setting mechanism, including a movable controlling element; a warning device associated with said computing mechanism; means for bringing said warning device into action automatically consequent upon the setting of said valuating mechanism, and throwing said device out of action automatically at the restoration of said valuating mechanism; and a lock connected to said warning device to be operated thereby, and arranged to engage said controlling element, so as to prevent actuation of the latter until the said restoration of the valuating mechanism takes place.

19. The combination, with computing mechanism, a driver therefor, and means tending to automatically throw said driver into action; of a latch normally holding said automatic means against action; state-controlling mechanism, including a movable controlling element; releasing means for said latch; and locking means moved by said latch, during its release, into the path of said controlling element, so as to prevent movement of the latter until the driver has returned to normal position.

20. The combination, with computing mechanism, and a set of numeral keys for operating the same; of locking means for preventing operation of said keys; character-
 5 of-computation-controlling mechanism, including a movable controlling element; means for bringing about the movement of said controlling element, to throw said character-of-computation-controlling mechanism into action; and means operated by said controlling element, during and consequent upon its said movement, for rendering said locking means active until the active movement of said controlling element is completed.
- 10 21. The combination, with computing mechanism, and operating means therefor; of locking means for preventing the actuation of said operating means; state-controlling mechanism, including a movable controlling element; means for bringing about the movement of said controlling element, to throw said state-controlling mechanism into action; and means operated by said controlling element, during and consequent upon its said movement, for rendering said locking means active until the active movement of said controlling element is completed.
- 15 22. The combination with a computing mechanism including a nest of pins having values from "1" to "9," of a subtraction-setting mechanism for said computing mechanism including means arranged to set the "9" pins, said "9" pin setting means being arranged to move out of the way after actuation, and locking means for preventing the actuation of said computing mechanism in case said "9" pin setting means fails to clear 20 after an actuation of said subtraction-setting mechanism.
- 20 23. The combination, with computing mechanism; of a subtraction-setting mechanism therefor; a key movable in one direction to manually bring said setting mechanism into play; locking means for holding said key against return movement after having been moved in such direction; and means for automatically releasing said locking means when said key is subsequently moved farther in the same direction.
- 25 24. The combination, with computing mechanism; of a subtraction-setting mechanism therefor; a key movable in one direction to manually bring said setting mechanism into play; a pin connected to said key; a bolt engageable with said pin to lock said key against return movement, after having been moved in such direction; and a releaser for automatically disengaging said bolt from said pin when said key is subsequently moved farther in the same direction.
- 30 25. The combination with a computing mechanism, of a subtraction-setting mecha-
 nism for said computing mechanism, a subtraction key for manually bringing said subtraction mechanism into play, a pin connected to said subtraction key having a head thereon, a bolt having a head arranged to engage the head on said pin to lock said subtraction key, and a spring-pressed releaser connected to said key for disengaging said heads from each other to enable the release of said key from said bolt.
- 35 26. The combination with a computing mechanism, of means for throwing out said computing mechanism, a general operator for actuating said computing mechanism to run up a number, locking means for said throw-out means, releasing means for said locking means, and a cam brought into play at a movement of said general operator to actuate said releasing means and enable the releasing of said locking means.
- 40 27. The combination with a computing mechanism, of means for throwing out said computing mechanism, locking means for said throw-out means, a general operator for actuating said computing mechanism to run up a number, a shaft rotated at the actuation of said general operator, a cam on said shaft, and connections actuated by said cam for releasing said locking means.
- 45 28. The combination with a computing mechanism including a series of denominational devices, of a general operator acting to drive said devices variable amounts, a traveling carriage, connections enabling the selection of said denominational devices from said carriage, means for throwing out said computing mechanism, locking means for said throw-out means, and releasing means actuated by said general operator for disengaging said locking means.
- 50 29. The combination, with a computing mechanism, and a general operator therefor; of means for throwing said computing mechanism out of action; a member connected to actuate said throw-out means, having a pin thereon; a fixed member having an L-slot therein engaged by said pin, said slot acting to lock said actuating member in one position; a shaft rotatable at the actuation of said general operator; a cam on said shaft; and a link engaging said cam and connected to said actuating member, to release said pin from its locking position in said slot.
- 55 30. The combination with a typewriting mechanism including a carriage, of a computing mechanism, denomination-controlling means for according the denominations as computed by said computing mechanism with the denominations as written by said typewriting mechanism, throw-out means for rendering said denomination-controlling means ineffective, automatic driving means controlled from said carriage at the end of

a computing zone or column for running up a computation, and means actuated by said throw-out means for concomitantly throwing said automatic driving means out of 5 action.

31. The combination with a computing mechanism, of a general operator for actuating said computing mechanism, an automatic drive for said general operator 10 brought into play spontaneously at the end of a computing zone or column, a non-add key for throwing out said computing mechanism, and connections for enabling said non-add key to throw out said automatic 15 drive.

32. The combination with a computing mechanism, of an automatic drive for said computing mechanism, a subtraction-setting mechanism for said computing mechanism, 20 automatic controlling means for bringing said subtraction-setting mechanism into action, a non-add key for throwing out said computing mechanism, and connections enabling said non-add key to concomitantly 25 render said automatic drive and said automatic controlling means ineffective.

33. The combination, with a computing mechanism, and an automatic drive therefor; of an automatic subtraction-setting 30 mechanism; a controlling device for said automatic drive; a controlling device for said automatic setting mechanism; a non-add key; means operated thereby for simultaneously rendering both controlling devices 35 ineffective; and means connected to operate the last-named means independently of said key.

34. The combination, with a computing mechanism, and an automatic drive therefor; of an automatic subtraction-setting 40 mechanism; a controlling device for said automatic drive; a controlling device for said automatic setting mechanism; a non-add key; a latch operated thereby for simultaneously locking both controlling devices 45 against actuation; and means connected to operate said latch independently of said key.

35. The combination with a computing 50 mechanism, of an automatic drive for said computing mechanism, an automatic subtraction-setting mechanism for said computing mechanism, and means for concomitantly silencing said automatic drive and said automatic subtraction-setting mechanism.

36. The combination, with a computing mechanism, and an automatic drive therefor; of an automatic subtraction-setting 60 mechanism; a controlling device for said automatic drive; a controlling device for said automatic setting mechanism; a latch for locking both controlling devices against actuation; and separate devices connected to actuate said latch, one of said devices 65 acting to temporarily hold the latch in actuated

position, and the other to permanently hold said latch in actuated position.

37. The combination, with a computing mechanism, and an automatic drive therefor; of an automatic subtraction-setting 70 mechanism; a controlling device for said automatic drive; a controlling device for said automatic setting mechanism; a latch for locking both controlling devices against actuation; and separate devices connected to 75 actuate said latch, one of said devices acting to temporarily hold the latch in actuated position, and the other to permanently hold said latch in actuated position; said latch-actuating devices being operable and releasable independently of each other. 80

38. The combination, with a computing mechanism, and an automatic drive therefor; of an automatic subtraction-setting mechanism; and a key acting, at a single 85 operation thereof, to render said computing mechanism, said automatic drive and said automatic setting mechanism ineffective.

39. The combination, with a computing mechanism, and an automatic drive therefor; of an automatic subtraction-setting mechanism; a key acting, at a single operation thereof, to render said computing mechanism, said automatic drive and said automatic setting mechanism ineffective; and 90 means independent of said key for rendering said automatic drive and said automatic setting mechanism ineffective. 95

40. The combination with a computing mechanism, of driving means for said computing mechanism, a subtraction-setting mechanism for said computing mechanism, controlling means for said driving means, controlling means for said subtraction-setting mechanism, and a single lock common 100 to both said controlling means for preventing the action thereof. 105

41. The combination with a computing mechanism, of a subtraction-setting mechanism for said computing mechanism, a 110 detent for preventing the action of said subtraction-setting mechanism, controlling means for said detent, locking means for rendering said controlling means ineffective, and non-add key for temporarily throwing 115 out said computing mechanism and actuating said locking means.

42. The combination with a computing mechanism, of a subtraction-setting mechanism for said computing mechanism, a 120 detent for said subtraction-setting mechanism, releasing means for said detent, and locking means for said releasing means including a latch and a lever for manipulating said latch and having a lost motion relatively 125 thereto.

43. The combination with a computing mechanism, of a subtraction-setting mechanism for said computing mechanism, a detent for said subtraction-setting mechanism, 130

releasing means for said detent, locking means for said releasing means, said locking means including a latch and a lever for manipulating said latch, said lever having a lost motion with respect to said latch, means for manipulating said lever in one direction, and a spring for manipulating said lever in the opposite direction.

44. The combination with a computing mechanism, of a subtraction-setting mechanism for said computing mechanism, a detent for said subtraction-setting mechanism, releasing means for said detent, locking means for said releasing means, said locking means including a latch and a lever for manipulating said latch having a relative movement with respect thereto, a spring connecting said lever with said releasing means, and a spring connecting said latch with said releasing means.

45. The combination with a computing mechanism, of a subtraction-setting mechanism for said computing mechanism, a detent for said subtraction-setting mechanism, releasing means for said detent, locking means for said releasing means, said locking means including a latch, and a lever for manipulating said latch having a relative movement with respect thereto, a spring connecting said lever with said releasing means, and a spring connecting said latch with said releasing means, one of said springs being stronger than the other of said springs.

46. The combination with a computing mechanism, of a subtraction-setting mechanism for said computing mechanism, a detent for said subtraction-setting mechanism, releasing means for said detent, locking means for said releasing means, said locking means including a latch and a lever for manipulating said latch, said lever having a lost motion with respect to said latch, a spring connecting said lever with said releasing means, a spring connecting said lever with said latch, and locking means for holding said lever and said latch in their effective positions against the tension of said springs.

47. The combination with a computing mechanism, of automatic actuating mechanism for said computing mechanism, means for rendering ineffective said actuating mechanism including a latch and a lever for manipulating said latch having a lost motion with respect thereto, a spring connected to said lever and a spring connected to said latch, said springs opposing each other, and locking means for maintaining said latch and said lever in their effective positions against the tension of one of said springs.

48. The combination with a computing mechanism, of a movable subtraction bar, said computing mechanism including a series of settable pins corresponding to the

values from "1" to "9", a rocking "9" pin-setting bail, a hooked arm rigidly connected to said bail, and a hook pivoted on said subtraction bar and arranged to catch against the hook on said arm to pull the latter with it during the movement of said bar, so as to rock said bail.

49. The combination with a computing mechanism, of a movable subtraction bar, said computing mechanism including a series of settable pins corresponding to the values from "1" to "9", a rocking "9" pin-setting bail, a hooked arm rigidly connected to said bail, a hook pivoted on said subtraction bar and arranged to catch against the hook on said arm to pull the latter with it during the movement of said bar, so as to rock said bail, and means for tripping said hook out of engagement with the hook on said arm before said subtraction bar completes its movement to enable the return of said bail to its ineffective position.

50. The combination with a computing mechanism including a series of settable pins corresponding to the values from "1" to "9", of a rocking bail for setting the "9" pins, a subtraction bar, means for rocking said bail in one direction from said subtraction bar to actuate it, a spring for returning said bail after actuation, a general operator for actuating said computing mechanism to run up numbers, and an arm connected rigidly to said bail and arranged to be engaged by said general operator to rock said bail in the opposite direction and thereby positively return it to its cleared position.

51. The combination with a computing mechanism, of a subtraction-setting mechanism for said computing mechanism, a detent for said subtraction-setting mechanism, releasing means for said detent, a spring for actuating said releasing means, a general operator for actuating said computing mechanism to run up a number, and a cam arm connected to said releasing means and located in the path of said general operator to be actuated thereby, to return said detent and retension said spring.

52. The combination with a computing mechanism, of a subtraction-setting mechanism for said computing mechanism, a subtraction bar for actuating said subtraction-setting mechanism, a spring normally under tension, tending to actuate said bar, a detent for said bar, manual means for releasing said detent, and automatic means for releasing said detent.

53. The combination, with a computing mechanism, driving mechanism therefor, and a traveling carriage; of subtraction-setting mechanism, including a movable controlling element; tripping mechanism for bringing said driving mechanism into play, operated automatically at a predetermined

point in the travel of the carriage; and locking means operated automatically at the operation of said tripping mechanism for blocking the movement of said controlling element, to prevent the operation of said setting mechanism.

54. The combination, with a computing mechanism, and a traveling carriage; of driving mechanism for said computing mechanism, including a movable controlling element; subtraction-setting mechanism, including a movable controlling element; tripping mechanism for bringing into play the driving mechanism controlling element, operated automatically at a predetermined point in the travel of the carriage; tripping mechanism for bringing into play the setting mechanism controlling element, operated automatically at a predetermined point in the travel of the carriage; and locking means operated automatically consequent upon the bringing into play of one of said controlling elements by its respective tripping mechanism, for blocking the movement of the other controlling element, to prevent the operation of the automatic mechanism associated with said other controlling element.

55. The combination with a computing mechanism, of a subtraction-setting mechanism for said computing mechanism including a subtraction bar, driving means for said computing mechanism, a roll-back connected to said automatic tripping mechanism, and a ward connected to said subtraction bar, said ward and said roll-back co-operating to alternatively prevent the bringing into play of said subtraction-setting mechanism or said automatic tripping mechanism according to whether one or the other is in an initial stage of operation.

56. The combination with a computing mechanism, of a subtraction-setting mechanism for said computing mechanism including a subtraction bar, driving means for said computing mechanism, a latch for controlling the action of said driving means, a trip for said latch, a ward on said subtraction bar, and a roll-back connected to be actuated by said latch to move into an obstructing position in the path of said ward to prevent the actuation of said subtraction bar and said subtraction-setting mechanism while said latch is released.

57. The combination with a computing mechanism, of a subtraction-setting mechanism for said computing mechanism including a subtraction bar, driving means for said computing mechanism, a latch for controlling the action of said driving means, a trip for said latch, a ward on said subtraction bar, and a roll-back connected to be actuated by said latch to move into an obstructing position in the path of said ward to prevent the actuation of said subtraction bar and said

subtraction-setting mechanism while said latch is released, said ward acting at times to prevent the movement of said roll-back and the release of said latch when said subtraction-setting bar has started in action and before finishing its movement.

58. The combination, with a computing mechanism, and a general operator therefor, including a rotary shaft; of a subtraction-setting mechanism for said computing mechanism including a subtraction bar; a dog on said shaft adapted to engage said bar, to lock the bar against actuation; a spring normally urging said dog into such engagement; and means on said shaft engageable with said dog while the shaft is stationary, to prevent said dog from engaging said bar.

59. The combination, with a computing mechanism, and a general operator therefor, including a rotary shaft; of a subtraction-setting mechanism for said computing mechanism including a subtraction bar; a dog on said shaft adapted to engage said bar, to lock the bar against actuation, said dog having a projecting arm; a spring normally urging said dog into such engagement; and an arm on said shaft arranged to engage the first-named arm while the shaft is stationary, to prevent said dog from engaging said bar.

60. The combination, with a computing mechanism, and operating means therefor; of a subtraction-setting mechanism for said computing mechanism including a subtraction bar; a detent normally locking said bar against actuation, and normally releasable therefrom to permit its actuation; and a detent brought into play automatically, consequent upon motion being imparted to said operating means, to lock said bar against actuation when the first-named detent is released, so long as said operating means continues in motion.

61. The combination, with a computing mechanism, and operating means therefor; of a subtraction-setting mechanism for said computing mechanism including a subtraction bar; a detent normally locking said bar against actuation, and normally releasable therefrom to permit its actuation; a detent brought into play automatically, consequent upon motion being imparted to said operating means, to lock said bar against actuation when the first-named detent is released, so long as said operating means continues in motion; and means actuated by said operating means at the conclusion of its motion for rendering the second-named detent ineffective.

62. The combination, with a computing mechanism, operating means therefor, and movable controlling means for bringing said operating means into play; of a traveling carriage; a member under the control of said carriage for automatically actuating

said controlling means at a definite point in the travel of the carriage; subtraction-setting mechanism associated with said computing mechanism and including a subtraction bar; and a member carried by said bar for movement therewith into position to block the movement of said controlling means to prevent its actuation by said carriage-controlled member until said bar has

10 completed its active movement.

63. The combination, with a computing mechanism, operating means therefor, and movable controlling means for bringing said operating means into play; of a traveling carriage; a member under the control of said carriage for automatically actuating said controlling means at a definite point in the travel of the carriage; a swinging member connected with said controlling means to be operated thereby; subtraction-setting mechanism associated with said computing mechanism and including a subtraction bar; and a member carried by said bar and movable therewith into the path of said swinging member, to prevent the actuation of said controlling means by said carriage-controlled member until said bar has completed its active movement.

64. The combination, with a computing mechanism, operating means therefor, and movable controlling means for bringing said operating means into play; of a traveling carriage; a member under the control of said carriage for automatically actuating said controlling means at a definite point in the travel of the carriage; subtraction-setting mechanism associated with said computing mechanism and including a subtraction bar having a projection thereon; a member movable into the path of said projection, to prevent actuation of said bar; and a member connected to be operated by said controlling means when the latter is actuated for shifting said movable member into such position at the moment when said operating means is brought into play.

65. The combination, with a typewriting mechanism; of a computing mechanism including a general operator for running up
50 a computation, and also including an indexing mechanism arranged to be actuated from said typewriting mechanism; a non-add key for freeing said indexing mechanism from subservience to said typewriting
55 mechanism, so as to enable the independent actuation of said typewriting mechanism; locking means for maintaining said non-add key in actuated position; releasing means for said locking means; and a cam brought
60 into play by a movement of said general operator and operable upon said releasing means to actuate the same.

66. The combination, with a computing mechanism; of means for throwing out said 65 computing mechanism including a thrust

rod; locking means associated with said rod, to hold the same in actuated position; a spring-controlled releasing arm pivoted to said rod; a general operator for actuating said computing mechanism to run up numbers; a shaft rotated at the actuation of said general operator; and a cam on said shaft arranged to engage and actuate said releasing arm. 70

67. The combination, with a computing mechanism including a nest of pins having values from "1" to "9"; of a subtraction-setting mechanism for said computing mechanism including means to set the "9" pins, said "9" pin-setting means being arranged to move out of the way after action; locking means for preventing the actuation of said computing mechanism; and means for automatically actuating said locking means in case said "9" pin-setting means fails to clear after an actuation of said subtraction-setting mechanism, the last-named means including a bell-crank operative by said "9" pin-setting means, a rock shaft operatively connected to said locking means, and a connection between said rock shaft and said bell-crank for operating the former from the latter.

68. The combination, with a computing mechanism including a nest of pins having values from "1" to "9"; of a subtraction-setting mechanism for said computing mechanism including means to set the "9" pins, said "9" pin-setting means being arranged to move out of the way after action; locking means for preventing the actuation of said computing mechanism; and means for automatically actuating said locking means in case said "9" pin-setting means fails to clear after an actuation of said subtraction-setting mechanism; the last-named means including a bell-crank-operative by said "9" pin-setting means, a rock shaft, a spring-controlled arm loose on said rock shaft and arranged to directly engage said locking means, and a connection between said rock shaft and said bell-crank for operating the former from the latter. 95 100 105 110

69. The combination, with a computing mechanism; of an automatic drive for said computing mechanism including a controlling lever; an automatic subtraction-setting mechanism for said computing mechanism including a controlling lever; a single element for concomitantly locking both of said levers against operation; and means for operating said locking element. 115 120

70. The combination, with a computing mechanism; of an automatic drive for said computing mechanism including a controlling lever; an automatic subtraction-setting mechanism for said computing mechanism including a controlling lever; a single element having separate portions thereof engageable with both of said levers, for con- 130

comitantly locking the same against operation; and means for operating said locking element.

71. The combination, with a computing mechanism; of an automatic drive for said computing mechanism including a controlling lever; an automatic subtraction-setting mechanism for said computing mechanism including a controlling lever; a pivoted latch arranged to simultaneously engage both of said levers, to lock the same against operation; and means for operating said latch.

72. The combination, with a computing mechanism; of an automatic drive for said computing mechanism including a controlling lever; an automatic subtraction-setting mechanism for said computing mechanism including a controlling lever; a pivoted latch having a hook arranged to engage one of said levers and a projection to engage the other lever, to simultaneously lock both levers against operation; and means for operating said latch.

73. The combination, with a computing mechanism; of an automatic drive for said computing mechanism including a controlling lever; an automatic subtraction-setting mechanism for said computing mechanism including a controlling lever; a single element for concomitantly locking both of said levers against operation; an operating member for said element arranged to temporarily hold it in operated position; and a second operating member for permanently holding said element in operated position.

74. The combination, with a computing mechanism; of an automatic drive for said computing mechanism including a controlling lever; an automatic subtraction-setting mechanism for said computing mechanism including a controlling lever; a single element for concomitantly locking both of said levers against operation; a controlling lever connected to said locking element; a member for temporarily holding said last-named controlling lever in operated position; and a separate member for permanently holding said last-named controlling lever in operated position.

75. The combination, with a computing mechanism; of an automatic drive for said computing mechanism including a controlling lever; an automatic subtraction-setting mechanism for said computing mechanism including a controlling lever; a single element for concomitantly locking both of said levers against operation; a controlling lever connected to said locking element; a non-add key for temporarily holding said last-named controlling lever in operated position; and a member separate from said key for permanently holding said last-named controlling lever in operated position.

76. The combination, with a computing

mechanism; of an automatic drive for said computing mechanism including a controlling lever; an automatic subtraction-setting mechanism for said computing mechanism including a controlling lever; a pivoted latch arranged to simultaneously engage both of said levers, to lock the same against operation; and separate, manually-operable members for temporarily and permanently holding said latch in operated position.

77. The combination, with a computing mechanism; of an automatic drive for said computing mechanism including a controlling lever; an automatic subtraction-setting mechanism for said computing mechanism including a controlling lever; a pivoted latch arranged to simultaneously engage both of said levers, to lock the same against operation; a controlling lever connected to operate said latch; and separate, manually-operable members for actuating the last-named controlling lever arranged to temporarily and permanently hold the same and said latch in operated position.

78. The combination, with a computing mechanism including a series of settable pins having values from "1" to "9"; of a rocking bail for setting the "9" pins having a hooked arm rigidly connected to it; a movable subtraction bar; a two-armed member pivoted to said bar, one arm of said member being arranged to engage said hooked arm during movement of the bar in one direction, to pull said hooked arm with it and thereby rock said bail; and a disconnecting element arranged to strike against the other arm of said member before said bar completes such movement, to trip said member and enable the return of said bail to ineffective position.

79. The combination, with a computing mechanism including a series of settable pins having values from "1" to "9"; of a rocking bail for setting the "9" pins having a hooked arm rigidly connected to it; a movable subtraction bar; a hook pivoted on said bar and arranged to catch against the hook on said arm, to pull the latter with it during the movement of said bar and thereby rock said bail; a general operator for actuating said computing mechanism to run up numbers; and an arm connected to said bail engageable by said general operator, to positively return said bail to its cleared position.

80. The combination, with a computing mechanism including a series of settable pins having values from "1" to "9"; of a rocking bail for setting the "9" pins having a pair of arms rigidly connected to it; a movable subtraction bar; a member on said bar arranged to engage one of said arms, during the movement of said bar, to pull said arm with it and thereby rock said bail in one direction to actuate it; means for tripping said member out of such engagement before said bar completes its movement, to release said bar

bail; and a general operator for actuating said computing mechanism to run up numbers, said general operator being arranged to engage the other of said arms subsequent to the release of said bail, to rock said bail in the other direction and thereby positively return it to its cleared position.

81. The combination with a register and actuating means therefor, of means for changing the condition of the actuating means to cause either addition or subtraction to be performed, a member to control the condition-changing means provided with a shoulder, a spring tending to actively drive said member, a latch normally engaged with said shoulder to restrain said member, and a manually-operable rocker arranged to force said latch out of such engagement.

82. The combination with a register and actuating means therefor, of means for changing the condition of the actuating means to cause either addition or subtraction to be performed, a member to control the condition-changing means, a spring tending to actively drive said member, means to restrain said member, and a manually-operable rocker for releasing said restraining means.

83. The combination with a register and actuating means therefor, of means for changing the condition of the actuating means to cause either addition or subtraction to be performed, a member to control said condition-changing means, a spring to actively drive said member, a latch to restrain said member normally engaged therewith, a carriage having means to automatically release said latch, and a manually-

operable rocker engageable with said latch, to release the same.

84. The combination with a register and actuating means therefor, of means to change the condition of the actuating means to cause either addition or subtraction to be performed, a member to control the condition-changing means, a spring tending to actively drive said member, a latch to restrain said member, a carriage, and separate carriage-controlled and manually-operable devices operatively associated with said latch to directly release the same.

85. The combination with a register and actuating means therefor, of shiftable means for changing the condition of the actuating means, a shifter for operating said shiftable means, a spring tending to actively drive said shifter, a latch to restrain said shifter, a carriage, and separate carriage-controlled and manually-operable devices for immediately releasing said latch.

86. The combination with a register and actuating means therefor, of shiftable means for changing the condition of the actuating means, a shifter-bar for operating said shiftable means, a spring tending to actively drive said bar, a latch normally engaged with said bar to restrain the same, a carriage, and separate carriage-controlled and manually-operable devices for immediately engaging said latch to release it from said bar.
